LOCOMOTIVE FRONT END

Leslie R. Pyle, Chicago, Ill., assignor to Locomotive Firebox Company, Chicago, Ill., a corporation of Delaware

Application February 12, 1940, Serial No. 318,405

9 Claims. (Cl. 230—97)

This invention relates to improvements in locomotive front ends and especially to those embodying a circumferentially open spark arrester in the smokebox and it consists of the matters hereinafter described and more particularly pointed out in the appended claims.

Locomotive front ends equipped with spark arresters of this kind, have certain objections which the present invention seeks to overcome. Heretofore, in such front ends, the baffles employed in connection with the arrester were so formed and disposed in the smokebox shell that the products of combustion entering the shell, on their way to the arrester, had to take a curved path under the arrester before they could enter the same. Therefore, the products of combustion could not travel around the entire smokebox shell, so that the draft action was not equalized throughout all the flue openings in the flue sheet.

Also, in such front ends as heretofore constructed, a relatively high exhaust pipe was necessary so that the overall height of the stack had to be decreased with a corresponding reduction in draft action of the locomotive. Again, when the front end contained superheater headers and tube ends, they could not be readily inspected or serviced without removal of the baffle plate.

Furthermore, with such front ends, by reason of the path which the products of combustion were forced to take, cinder cutting occurred under the table plate and also on the front of the smokebox shell. Again, such products of combustion quickly accumulated in the front end as a whole, and made frequent servicings and consequent laying up of the locomotive, necessary.

One of the objects of the present invention is to provide a structure for an arrester equipped front end of this kind wherein the standard vertical baffle plate and table plate may be eliminated and at the same time a better and equalized draft action through all the flues in the flue sheet may be obtained.

It is also an object of the invention to provide a construction in which there shall be but a minimum amount of cinder cutting of the smokebox shell and parts within the same.

Another object of the invention is to provide an arrangement in a front end of this kind wherein it is possible to employ a low exhaust pipe to increase the overall height of the stack thereby to obtain a better draft action.

Also, it is an object of the invention to provide a front end structure of this kind whereby a better breaking down of the unburned particles of

combustion, as well as a better entraining action is obtained and which structure is self-cleaning because the products of combustion are not confined to a path of travel from which they can settle out and accumulate in the front end.

A further object of the invention is to provide a structure in a front end of this kind which may be more easily inspected and serviced than has heretofore been possible and at the same time is more convenient for working upon the superheater units and flue sheet with a minimum disturbance of the arrester itself.

The above-mentioned objects of the invention, as well as others, together with the advantages thereof will more fully appear as the specification proceeds.

In the drawings:

Fig. 1 is a longitudinal vertical sectional view through a locomotive front end embodying the preferred form of the invention;

Fig. 2 is a horizontal sectional view through the front end structure appearing in Fig. 1 as taken on the line 2—2 thereof;

Fig. 3 is a transverse vertical sectional view through the improved locomotive front end as taken on the line 3—3 of Fig. 1;

Fig. 4 is a longitudinal vertical sectional view through a locomotive front end embodying a modified form of the invention;

Fig. 5 is a horizontal sectional view through the structure appearing in Fig. 4 as taken on the line 5—5 of Fig. 4, and

Fig. 6 is a transverse vertical sectional view through the structure appearing in Fig. 4 as taken on the line 6—6 of said Fig. 4.

Referring now in detail to that embodiment of the invention illustrated in Figs. 1, 2 and 3 of the drawings, 5 indicates the tubular body of a locomotive smokebox shell, which is suitably connected at its rear end to the front end of the boiler shell 6 of the locomotive in any suitable manner. The smokebox shell is separated from the water space of said boiler shell by the flue sheet 7. The ends of flues 8 are secured in said flue sheet to open into the smokebox shell so as to deliver thereto, the products of combustion from the firebox of the locomotive. 9 indicates the front of the smokebox shell having the usual door 10 therein.

11 indicates the flanged base for the smoke stack and which base is directly attached to the top of the smokebox shell about an opening 12 therein. Said base includes a tubular portion 13 that depends into the interior of the smokebox

shell and is adapted for the attachment of an extension thereto as will later appear.

The exhaust stand or pipe which is indicated at 14, rises from the bottom of the smokebox shell 5 in axial alignment with the tubular portion 13 of the stack base. This pipe which is relatively low or short, is flanged at its top end as at 15 to receive a coacting flange 16 on an exhaust nozzle or tip 17 of any approved kind.

In the smokebox shell is located an arrester of the so-called circumferentially open type and the same is indicated as a whole at 18. Such an arrester, which is cylindrical in shape, has its axis arranged in alignment with the axes of both the tubular portion 13 and the tip or nozzle 17. It comprises vertically spaced apart top and bottom plates 19—20 respectively and perpendicular vanes or deflector plates 21 fixed at their ends to said plates. The top plate, which is circular, has a central opening which receives the bottom end portion of a stack extension 22 with a sliding fit. Preferably the top plate 19 is made of front and rear, detachably connected, semi-circular parts as appears in Fig. 2, for installation purposes and wherewith it is unnecessary to dismantle the stack during installation. The top plate 19 is provided with a flanged ring 19a about the opening before referred to, to provide a better engagement with the smoke stack extension, the upper end of which is attached to the tubular portion of the smoke stack base 13.

The bottom plate 20 of the arrester is engaged in supporting relation upon a horizontally disposed table plate 28, disposed in the plane of the top of the exhaust pipe flange 15 and upon which it engages. The side edges of this table plate rest upon opposite side portions of the smokebox shell, while its front edge engages against a part of the front 9. Its rear edge is disposed coincident with the circle of the arrester bottom plate 20 when considered on the longitudinal center line of the smokebox shell 5. A vertically disposed partition 23 is provided between the rear edge of the table plate 28 and the associated bottom portion of the smokebox shell. Thus the table plate 28 and the partition 23 coat with parts of the smokebox shell and its front in providing a blocked-off dead air space 24 in the bottom front end portion of the smokebox shell and in which the exhaust pipe 14 is disposed.

With the arrangement described, room or space is present at opposite sides of the arrester 18 for the passage of steam pipes 25 that lead to the cylinders of the locomotive of which the smokebox shell forms a part. These pipes have a flanged upper end connection with superheater headers 26 in the upper rear portion of the smokebox shell. Said pipes and said superheater headers, as well as the superheater tubes 27 best appear in dotted lines in Fig. 1 of the drawings.

It is pointed out at this time that the vanes or deflectors 21 of the arrester, which may be curved transversely are shown in Fig. 2 as being straight transversely. They are disposed tangentially to the axis of the arrester as a whole, and extend inwardly from the circle of the top and bottom plates 19 and 20 to terminate short of the circle of the stack extension 22.

30 indicates as a whole a baffle or deflector plate disposed in a generally upright, transverse position between and in spaced relation with respect to both the flue sheet 7 and the rear of the arrester 18 as a whole. As shown in Figs. 1 and 2, said baffle includes a main upright por-

tion 31 and an upwardly and forwardly extending portion 32 arranged in a plane substantially parallel to the adjacent portions of the superheater tubes 27 that lead to the header 26. The baffle, as a whole, is of a width less than the diameter of the smokebox shell so that there is a space between each side edge thereof and the adjacent side portions of the smokebox shell.

The bottom edge of the main upright portion of the baffle is disposed in a plane a short distance below the table plate and the top end of said portion joins its extension 32 a slight distance below the top of the arrester. The top edge of the extension 32 is disposed below the superheater header 26, permitting access to the header for inspection without removing the baffle plate 30. The bottom end corners of the baffle are cut away as seen from Fig. 3, to fit against portions of the sides of the smokebox shell and are preferably welded thereto. The upper portion of the baffle as a whole, may be secured in place by suitable braces (not shown) attached to the smokebox shell and whereby the baffle is rigidly held in position in the smokebox shell.

It is apparent from the above, that as the products of combustion enter the smokebox shell, the major portion thereof impinge against the rear face of the baffle 30 usually with an impact that reduces the larger particles of said products to a smaller size. Then said major portion of said products of combustion are deflected upwardly, downwardly and laterally, to pass over, under and about the side edges of the baffle with an attrition action that further reduces the size of said particles. Thus, as said products of combustion pass about the various edges of the baffle, they are distributed in a more even manner so as to be substantially equalized in volume before they enter that part of the smokebox shell forward of the baffle. When said products of combustion are thus equalized, they enter the arrester in approximately the same volume or proportion entirely about the periphery of the arrester casing. The movement of the products of combustion is induced by the draft action of the jet discharged from the nozzle 14 and which action causes an entrainment of said particles for discharge out through the stack. As the products of combustion are not confined to a single path from the flues to the arrester, but may travel around the entire smokebox shell, this equalizes the draft throughout all of the flues 8 opening through the flue sheet 7. Therefore, there are no substantially "dead" flues to produce spotty burning of the fuel in the firebox of the locomotive.

By reason of the structure described, no part of the products of combustion can pass into the space 24. As the products of combustion are evenly distributed about the smokebox shell forward of the baffle 30, said products enter the arrester casing about the entire periphery thereof. Therefore, no part of the products of combustion can settle out onto the table plate on their way to the arrester due to faulty draft action so that the front end as a whole, is self-cleaning.

In Figs. 4, 5 and 6, I have illustrated a somewhat modified form of construction for the baffle plate, in that a duplex arrangement is employed. Therefore, all parts other than the modified form of baffle plate construction are substantially the same as before described and bear the same reference numerals. In said Figs. 4, 5 and 6, 35 indicates a main upright baffle or

deflector plate disposed between and in spaced relation with respect to both the flue sheet 7 and the rear of the arrester 18, as a whole. As shown in Figs. 4 and 5, this plate is curved transversely of the smokebox shell and is made as an arc of a circle having its axis disposed forwardly of the axis of the arrester. The bottom edge of said plate is shown as disposed in substantially the plane of the bottom plate 20 of the arrester and the top edge of said plate 35 is disposed in a plane above that of the top plate 19 of the arrester. The side edges 36 of said plate 35 are perpendicular as shown, so as to leave a space between them and adjacent portions of the smokebox shell. The lower corners of said plate are cut away for engagement with portions of the smokebox shell and to which they are welded to support the plate in the desired position. If desired, other points of said baffle plate may be braced from convenient points of the smokebox shell.

37 indicates a secondary upright baffle plate that rises from the top plate 19 of the arrester and spaced rearwardly from the stack extension 22. This plate 37 which is also curved transversely of the smokebox shell, is made as an arc of a circle having the same radius as that of the plate 35 but with its axis disposed forwardly of the axis of said plate 35. The side edges of said secondary plate, which are perpendicular, are disposed substantially on spaced points of the circle of the top plate 19 of the arrester. The top edge of the plate 37 terminates in a plane below that of the superheater header so as to give full access to the header for inspection.

In this construction, those parts of the products of combustion which impinge against the main deflector plate 35, pass about the various edges thereof seeking entrance into the arrester. Those parts of the products of combustion which impinge against the secondary deflector plate 37, pass about the side edges and the top edges of said plate before they pass to the front of the smokebox to enter the arrester. The plates 35 and 37 are so formed in area and are so positioned in the smokebox with respect to the arrester as to provide a substantially equalized distribution in volume for the products of combustion before they enter said arrester about its circumference. Thus with this arrangement of baffle plates, as with the arrangement shown in Figs. 1, 2 and 3, there are no "dead" flues or no "dead" areas in the smokebox shell or about the circumference of the arrester to produce eddies that interrupt the velocity of said products of combustion. Thus draft action in the firebox is not "spotty" nor do back pressures build up in the smokebox to interfere with said draft action.

The structures described embody no moving parts to get out of order. They are simple and may be readily installed in locomotives now equipped with arresters of this type. Also said baffles may be readily replaced by new ones when worn through.

While in describing the invention, I have referred in detail to the form, arrangement and construction of the parts involved, the same is to be considered only in the illustrative sense so that I do not wish to be limited thereto except as may be specifically set forth in the appended claims.

I claim as my invention:

1. In combination with the smokebox shell of a locomotive having a flue sheet at one end thereof, a circumferentially open spark arrester in said

shell, a smoke stack having a portion arranged in the shell and operatively disposed with respect to the upper portion of said arrester, an exhaust nozzle arranged to discharge into the bottom of said arrester, and means arranged in said smokebox shell between said flue sheet and said arrester and so formed that products of combustion must pass over, under and laterally about the same to assist in equalizing the distribution of the products of combustion in said smokebox shell before they enter said arrester about substantially its entire periphery.

2. In combination with the smokebox shell of a locomotive having a flue sheet at one end thereof, a circumferentially open spark arrester in said shell, a smoke stack having a portion arranged in the shell and operatively disposed with respect to the upper portion of said arrester, an exhaust nozzle arranged to discharge into the bottom of said arrester, means providing a closed off dead air space in the forward bottom portion of the smokebox shell and the top of which space is substantially coincident with the bottom of the arrester, and means arranged in said smokebox shell between said flue sheet and said arrester and so formed that products of combustion must pass over, under and laterally about the same to assist in equalizing the distribution of the products of combustion in said smokebox shell before they enter the arrester about substantially its entire periphery.

3. In combination with the smokebox shell of a locomotive having a flue sheet at one end thereof, a circumferentially open spark arrester in said shell, a smoke stack having a portion arranged in the shell and operatively disposed with respect to the upper portion of said arrester, an exhaust nozzle arranged to discharge into the bottom of said arrester, and means arranged in said smokebox shell between said flue sheet and said arrester and having top and bottom portions disposed in planes above and below the planes of the top and bottom of the arrester and having side margins spaced from adjacent parts of the smokebox sheet to assist in equalizing the distribution of the products of combustion in said smokebox shell before they enter said arrester about substantially its entire periphery.

4. In combination with the smokebox shell of a locomotive having a flue sheet at one end thereof, a circumferentially open spark arrester in said shell, a smoke stack having a portion arranged in the shell and operatively disposed with respect to the upper portion of said arrester, an exhaust nozzle arranged to discharge into the bottom of said arrester, a plate-like member disposed substantially in the plane of the bottom of said arrester casing and extending forwardly thereof to the front of the smokebox shell and having lateral edges engaged with opposite side portions of the smokebox shell, a partition depending from the rear end of the plate-like member and engaged with the bottom portion of the smokebox shell and coacting with said plate-like member in providing a closed off space in the forward bottom portion of the smokebox shell, and means arranged in the smokebox shell between said flue sheet and said arrester and so formed that products of combustion must pass over, under and laterally about the same to assist in equalizing the distribution of the products of combustion before they enter said arrester about substantially its entire periphery.

5. In combination with the smokebox shell of a locomotive having a flue sheet at one end there-

of, a circumferentially open spark arrester in the smokebox shell, a smoke stack having a portion arranged in the smokebox shell and operatively disposed with respect to the upper portion of the spark arrester, an exhaust nozzle arranged to discharge into the bottom of the spark arrester and coacting with the stack in inducing a draft action in the spark arrester, and means providing a baffle between but in spaced relation with respect to both the flue sheet and the adjacent portion of the spark arrester, said baffle being formed to permit the passage of the products of combustion above its top edge, below its bottom edge and about its side edges on their way from the flues to the spark arrester.

6. In combination with the smokebox shell of a locomotive having a flue sheet at one end thereof, a circumferentially open spark arrester in the smokebox shell, a smoke stack having a portion arranged in the smokebox shell and operatively disposed with respect to the upper portion of the spark arrester, an exhaust nozzle arranged to discharge into the bottom of the spark arrester and coacting with the stack in inducing a draft action in the spark arrester, means for closing off the bottom of the spark arrester from the forward bottom portion of the smokebox, and means providing a baffle between but in spaced relation with respect to both the flue sheet and the adjacent portion of the spark arrester, said baffle being formed to permit the passage of the products of combustion above its top edge, below its bottom edge and about its side edges on their way from the flues to the spark arrester.

7. In combination with the smokebox shell of a locomotive having a flue sheet at one end thereof, a circumferentially open spark arrester in the smokebox shell, a smoke stack having a portion arranged in the smokebox shell and operatively disposed with respect to the upper portion of the spark arrester, an exhaust nozzle arranged to discharge into the bottom of the spark arrester and coacting with the stack in inducing a draft action in the spark arrester, and means providing an upright baffle member extending transversely of the smokebox shell and arranged

in spaced relation to both the flue sheet and the adjacent portion of the spark arrester, said baffle being formed to permit the passage of the products of combustion above its top edge, below its bottom edge and about its side edges on their way from the flues to the spark arrester.

8. In combination with the smokebox shell of a locomotive having a flue sheet at one end thereof, a circumferentially open spark arrester in the smokebox shell having a top and a bottom, a smoke stack having a portion arranged in the smokebox shell and opening through the top of the spark arrester, an exhaust nozzle opening through the bottom of the arrester and coacting with the stack in inducing a draft action in the arrester, an upright baffle between but in spaced relation with respect to both the flue sheet and the adjacent portion of the arrester, said baffle including an upwardly and forwardly extending top end portion, said baffle being formed to permit the passage of the products of combustion above its top edge, below its bottom edge and about its side edges on their way from the flues to the spark arrester.

9. In combination with the smokebox shell of a locomotive having a flue sheet at one end thereof, a circumferentially open spark arrester in the smokebox shell having a top and a bottom, a smoke stack having a portion arranged in the smokebox shell and opening through the top of the spark arrester, an exhaust nozzle opening through the bottom of the arrester and coacting with the stack in inducing a draft action in the arrester, means extending forwardly from the bottom of the arrester for closing off the same from the forward bottom portion of the smokebox shell, and a baffle between but in spaced relation with respect to both the flue sheet and the rear of the arrester, and including an upwardly and forwardly extending top end portion, said baffle being formed for the passage of the products of combustion above its top edge, below its bottom edge and about its side edges, on their way from the flues to the spark arrester.

LESLIE R. PYLE.
